JOURNAL BOX LID

Harry J. Horn, Lansing, Mich., assignor to Motor
Wheel Corporation, Lansing, Mich., a corpora-
tion of Michigan

Application February 3, 1941, Serial No. 377,113

8 Claims. (Cl. 308—47)

This invention relates to railway car journal boxes, and more particularly to hinged lids therefor.

Journal box lids in common use at present are formed of two major parts, namely, a hood pivotally connected to a hinge lug on the journal box, and a cover connected to the hood for limited universal movement relative thereto. The last mentioned connection is ordinarily very loose to permit the cover to adjust itself to the rim of the opening in the journal box. A spring is connected to the hood to engage the hinge lug on the journal box and hold the journal box lid either in open or closed position. Heretofore this spring has been the only means for preventing undue relative movement between the hood and cover when the lid is closed. The spring does not prevent such movement when the cover is open. When the hinge lug wears sufficiently, considerable movement of all of the parts is permitted, resulting in wear in the connection between hood and cover, particularly in the bolt or pin that holds them together. Often the pin wears completely through and the cover drops off and is lost.

Accordingly, it is the principal object of the invention to provide a journal box lid assembly wherein the hood and cover are so formed and so connected together that undue relative movement thereof is minimized, regardless of wear in the other parts of the assembly.

The essence of the invention resides in forming the hood and cover so that they engage each other in a zone remote from the stud or pin connecting them together, and providing resilient means independent of the usual closure spring for holding the hood and cover in tight frictional engagement in that zone.

In the following specification reference will be made to the accompanying drawing, wherein—

Figure 1 is a front elevational view of a journal box lid assembly embodying the invention;

Figure 2 is a cross-sectional view taken on substantially the line 2—2 of Figure 1;

Figure 3 is a cross-sectional view of a rubber ring forming a part of the means for holding the hood and cover together;

Figure 4 is a plan view of the ring;

Figure 5 is a fragmentary cross-sectional view of the journal box assembly illustrating a device for holding the closure spring in compressed position to permit removal of the lid from the journal box;

Figure 6 is a fragmentary front elevational

view showing a modified form of the invention; and

Figure 7 is a cross-sectional view taken on substantially the line 7—7 of Figure 6.

Figures 1 to 4 of the drawing illustrate one form of the invention. A portion of a standard A. R. A. journal box is shown in dotted lines in Figure 2 and designated by the numeral 10. At the upper end of the journal box and centrally thereof is a hinge lug 11 having a cam surface 12 thereon.

The journal box lid assembly is shown in full lines in Figures 1 and 2. It comprises generally a hood 13 and a cover 14.

The hood 13 is substantially rectangular in elevation (see Figure 1). At its opposite sides adjacent the upper ends thereof are ears 13a. The ears 13a are provided with apertures to receive a pintle 15 passing through the hinge lug 11 to hinge the hood to the journal box. The end of the pintle is split at 16 so that the ends may be separated to prevent accidental removal of the pintle.

Near the upper end of the hood is a coil spring 25 assembly comprising a housing 17 received in a hole in the hood. A hollow cylindrical plunger 18 is telescopically received in the housing 17. A plate 19 is riveted to the end of the plunger 18 and normally bears against the cam surface 12 of the hinge lug 11, being urged against said cam surface by a coil spring 20 within the plunger and housing.

The plate 19 is provided with a protuberance 21 that compensates to some extent for wear of the cam surface of the hinge lug. The plate is also provided with an aperture 22 axially aligned with a similar aperture 23 in the hood 13 to receive a bolt 24. The bolt 24 is employed only when the lid assembly is to be installed upon or removed from the journal box. When so used, the bolt 24 and a nut 25 thereon hold the spring 20 in compressed position, releasing its pressure on the hinge lug and permitting the pintle 15 to be removed.

Near its lower end, the hood is shaped to the cross-section shown in Figure 2, thus providing a substantially spherical recess 26 in its inner surface. Centrally of the recess is a hole 27, the purpose of which will appear presently.

The cover 14 is approximately rectangular in elevation and is provided about its periphery with a flange 28. The cover 14 is shaped to the cross-section shown in Figure 2 to provide an inwardly extending stiffening rib 29 and an outwardly projecting spherical protuberance 30. Centrally of

the protuberance is a hole 31. The radius of the spherical protuberance is greater than the radius of the recess 26 in the hood. Thus, when the protuberance 30 is positioned in the recess 26, the parts contact only on a circle concentric with and remote from the holes 27 and 31.

Projecting through the holes 27 and 31 is a stud 32. The stud 32 has a head 33 and a shank portion 34 of a diameter considerably smaller than the hole 27 but larger than the hole 31. The end of the stud opposite the head is threaded to receive a nut 35. The diameter of the threaded portion is such as to fit reasonably closely in the hole 31.

A rubber ring 36 (Figures 3 and 4) is enclosed within two annular metal rings 37 to protect it from the weather (see Figure 2) and is located between the head 32 of the stud and the outside surface of the hood. When the nut 35 is drawn up tightly the rubber ring is placed in compression, thus drawing the hood and cover tightly together. The end of the stud is then peened over to prevent removal of the nut 35.

From the above description it will be seen that the cover is capable of limited universal movement relative to the hood since the hole 27 is large enough for the stud to move therein. Thus, the cover 14 can adjust itself to the journal box so as to fit snugly thereon. The relatively heavy frictional contact between the two spherical surfaces of the recess and protuberance, caused by the compressed rubber ring 36, prevents relative movement of the hood and cover due to vibration. Therefore, the prevention of such relative movement is not dependent upon the spring 28 as in previous journal box lids, and there is little wear between the hood and cover. The life of the assembly accordingly is very long.

A modified form of the invention is shown in Figures 6 and 7. In general it is identical to the lid assembly previously described. It comprises a hood 13' having a recess 26', and a cover 14' having a spherical protuberance 30'. A stud 32' holds the two parts together.

Instead of a rubber ring, a metal spring 50 is provided to maintain the hood and cover in tight frictional engagement. The spring 50 is generally rectangular in elevation (see Figure 6) and has a hole in its center to receive the stud 32'. The corners 51 of the spring are bent out of the plane of the central portion of the spring toward the hood, as shown in Figure 7. The extreme tips of the corners are reversely bent whereby to present rounded surfaces 52 for engagement with the hood 13'.

The spring 50 acts in the same way as the rubber ring 36, being stressed by the stud when a nut 35' on the stud is threaded home, and thereby holding the hood and cover against undue relative movement. The resiliency of the spring does permit relative movement of the hood and cover whereby the latter automatically seats tightly against the rim of the journal box opening.

The invention provides a simple and effective means for minimizing relative movement of the hood and cover of a journal box lid assembly, regardless of wear of the journal box hinge lug and related parts.

The scope of the invention is indicated in the appended claims.

I claim:

1. A journal box lid assembly comprising a hood member adapted for pivotal connection to a journal box hinge lug, a cover member, one of

said members having a substantially spherical recess therein, the other member comprising a protuberance having a spherical surface of greater radius than the radius of said recess and received therein, and means securing said members together for limited universal movement of said protuberance in said recess, said means including resilient means biasing said members together.

2. A journal box lid assembly comprising a hood member adapted for pivotal connection to a journal box hinge lug, a cover member, one of said members having a substantially spherical recess, the other member comprising a protuberance having a substantially spherical surface of greater radius than the radius of said recess and received therein, a stud secured to one of said members centrally of said recess and loosely fitting in a hole in the other member, resilient means surrounding an end of said stud, and means on the end of said stud holding said resilient means in compressed position to bias said members together.

3. A journal box and lid assembly comprising, in combination, a hinge lug on the journal box, a hood member pivotally connected to said hinge lug, spring means connected to said hood and engaging said hinge lug for biasing said lid assembly toward its closed position, a cover member, and means securing said members together in frictional engagement with each other and permitting limited relative universal movement thereof, said connecting means including resilient means independent of said first named spring biasing said members toward each other.

4. A journal box and lid assembly comprising, in combination, a hinge lug on the journal box, a hood member pivotally connected to said hinge lug, spring means connected to said hood and engaging said hinge lug for biasing said lid toward its closed position, a cover member, and means securing said members together for limited relative universal movement, said means including resilient means biasing said members toward each other, said members frictionally engaging each other at points remote from said securing means.

5. A journal box and lid assembly comprising, in combination, a hinge lug on the journal box, a hood member pivotally connected to the hinge lug, spring means connected to the hood and engaging the hinge lug for biasing said lid toward its closed position, a cover member, one of said members having a substantially spherical recess therein, the other member comprising a protuberance having a spherical surface of greater radius than the radius of said recess received in the latter, and means securing said members together including resilient means independent of said first named spring means biasing said members toward each other.

6. A journal box lid assembly comprising a hood member adapted for pivotal connection to a journal box, a cover member, one of said members having a recess and an opening therethrough located centrally of said recess, the other member having a protuberance received in said recess and touching the walls thereof only at points remote from said opening, a stud extending through said opening and securing said members together, and resilient means surrounding said stud for biasing said members toward each other.

7. A journal box lid assembly comprising a hood member, a cover member, one of said mem-

bers having a recess therein, the other member having a protuberance received in said recess, said recess and protuberance being shaped to permit limited universal relative movement of said members, said members having registering openings therein located centrally of said recess and protuberance, a stud of less diameter than the opening in one member extending therethrough, and resilient means surrounding said stud for biasing said members together.

8. A journal box lid assembly comprising a hood member, a cover member, and a resilient member in juxtaposed relationship, each of said

members having registering openings therein, one of said members being recessed in the zone surrounding the opening therein, another member having a protuberance received in said recess and touching the walls thereof only at points remote from said openings, and means extending through said openings for stressing said resilient member and holding said members in juxtaposed relationship while permitting limited movement of said protuberance within said recess.

HARRY J. HORN.
